UNITED STATES PATENT OFFICE.

ALTON H. FANCHER, OF BROOKLYN, NEW YORK, ASSIGNOR TO THE E. W. BLISS COMPANY, LIMITED, OF LONDON, ENGLAND.

DESIGN FOR A SPOON.

SPECIFICATION forming part of Design No. 21,836, dated September 6, 1892.

Application filed July 15, 1892. Serial No. 440,163. Term of patent 3½ years.

To all whom it may concern:

Be it known that I, ALTON H. FANCHER, a citizen of the United States, residing in Brooklyn, in the county of Kings and State 5 of New York, have invented and produced a certain new and original Design for Spoons, of which the following is a specification.

My new design for spoons is shown in the accompanying drawing, which is a face view 10 of a spoon to which the design is applied.

According to my new design the handle of the spoon is constructed with an enlarged handle end of the irregular outline indicated in the drawing, a reduced shank, and a 15 swelled body end where it connects with the bowl of the spoon.

As shown, the design for the handle end of the spoon consists of a waving flag, as a United States flag, at one side and a curved 20 band or ribbon at the other side, coiled and broadest at the outer end and tapering thence slightly toward the shank of the handle, where it crosses the extremity of the flag and is divided into two convoluted ends. The shaft 25 to which the flag is connected appears above this band. The outline of this portion of the handle consists of the lower edge of the band, its convoluted outer end, and the upper edge 30 of the flag. The shank of the handle joins the handle end at the divided end of the band and consists of a narrow and slightly tapering band, on which is disposed a row of 35 stars of gradually-diminishing size toward the body end. Each side of the shank is traversed by a narrow strip, that at one side 40 ending at the handle end in a slight scroll beneath the divided end of the band and that at the other side ending in contact with a similar curved strip extending from the central portion of the shank near the last star at the outer end thereof outwardly in a grace-

ful curve past the divided end of the band of the enlarged portion of the handle and terminating in two slight scrolls at the edge of the inner end of the flag. The body end of the 45 handle has a conventional figure of a bird, as an eagle, with spread wings, extending toward the shank and terminating the side strips thereof, between which wings the end star of the row of stars on the shank is disposed. 50 The neck of the bird is curved, its head lies slightly at one side, and in its claws are grasped a branch and some arrows.

According to my new design the bowl of the spoon carries the representation of a 55 group of people disposed in various positions on a shore, the sea and a vessel being shown in the background. The foremost person in the group is shown as standing hatless, with drawn sword in one hand and a banner in the 60 other, while certain of the group are kneeling. The people are shown as clothed in costumes of the fifteenth century. The representation is intended to be symbolical of the landing of 6 Columbus at the time of the discovery of America.

In carrying out my new design the various figures, ornaments, and representations may be applied either in relief or intaglio. They are shown in the accompanying drawing as 70 in relief.

What I claim as new is—

The design for a spoon, substantially as shown and described.

In witness whereof I have hereunto signed 75 my name in the presence of two subscribing witnesses.

ALTON H. FANCHER.
